UNITED STATES PATENT OFFICE

154,760

DESIGN FOR A MINE PASSENGER CAR

Henry Fort Flowers, Findlay, Ohio

Application February 4, 1947, Serial No. 136,678

Term of patent 14 years

(Cl. D66—1)

To all whom it may concern:

Be it known that I, Henry Fort Flowers, a citizen of the United States, residing at Findlay, in the county of Hancock and State of Ohio, have invented a new, original, and ornamental Design for Mine Passenger Car, of which the following is the specification, reference being had to the accompanying drawing, forming a part thereof.

In the drawings:

Figure 1 is a perspective view looking toward the front and left side of the mine passenger car, showing my new design;

Figure 2 is a perspective view looking toward the opposite end and opposite side;

Figure 3 is a plan view, and

Figure 4 is an end elevational view thereof as seen from the rear end in Figure 2.

The characteristic features of my design reside in the portions shown by means of full lines in the drawings.

I claim:

The ornamental design for a mine passenger car, as shown and described.

HENRY FORT FLOWERS.
